CLAIM

The ornamental design for an electrical test lead, as shown and described.

DESCRIPTION

FIG. 1 is a top front left isometric view of an electrical test lead showing our new design;

FIG. 2 is a top plan view thereof;

FIG. 3 is a bottom plan view thereof;

FIG. 4 is a rear elevation view thereof;

FIG. 5 is a front elevation view thereof;

FIG. 6 is an inverted right side elevation view thereof;

FIG. 7 is a left side elevation view thereof; and,

FIG. 8 is a top rear left isometric view thereof.

The broken lines shown in the drawings are directed to environment and form no part of the claimed design.
